ALARM-CLOCK

Friedrich Meyer, Grenchen, Switzerland, assignor to
Ebauches S.A., Neuchatel, Switzerland

Application January 28, 1958, Serial No. 711,624

Claims priority, application Switzerland
December 14, 1957

8 Claims. (Cl. 200—35)

This invention relates to an alarm-clock of the type comprising an electrically actuated alarm-apparatus, particularly a radio receiver, an electric power source, a timepiece and switch means electrically connected between the said power source and the said alarm-apparatus and controlled by the said timepiece, and adjusting means in the said switch means for selecting a predetermined moment in which the said switch means are closed by the said timepiece, thereby connecting the said alarm-apparatus to the said power source for actuating the said alarm-apparatus.

Particularly when a radio receiver is used as an alarm-apparatus it is required to obtain a sharp and distinct closure of the switch means in order to avoid sparking and rapid wear of the switch means and undesired noise in the radio receiver due to slow and indefinite switch operation. However, since the switch means have to be actuated by a control member mounted on the hour wheel of the timepiece, such control member being consequently displaced at an extremely low speed, rapid and concise switch operation cannot easily be obtained. Further, the disposable force or turning moment of the hour wheel of the timepiece for actuating the switch means is very limited, particularly when the timepiece is actuated by a balance wheel of which the oscillation is sustained electrically.

It is an object of this invention to provide switching means for an alarm-clock of the above type, meeting with the requirements set out above and adapted for proper operation at a minimum consumption of actuating force and actuating energy. The alarm-clock of this invention broadly comprises a contact member in the said switch means having a closed position and an open position, means continuously tending to bring the said contact member into its said closed position, actuating means operatively connected to the said timepiece and operatively associated with the said contact member, adapted to bring the said contact member into its open position under control of the said timepiece, and releasing means operatively associated with the said contact member and operatively connected to the said timepiece, adapted to release the said contact member from its said open position into its said closed position in the said predetermined moment. Preferably the said actuating means operatively associated with the contact member and operatively connected to the timepiece may be disposed in such a way that prior to any switch operation they are acting onto the contact member for an appreciable period of time, for instance for one hour, thereby slowly displacing the said contact member towards its open position and accumulating mechanical energy in the contact member, by which accumulated energy the switch is subsequently actuated rapidly and concisely.

In the attached drawings one embodiment of the invention is shown by way of example.

Fig. 1 is a view of the switch mechanism of the alarm-clock seen from below in Fig. 2 but with the mounting

2

plate and the minute wheel and the minute wheel pinion removed,

Fig. 2 is an axial section of the switch mechanism of the alarm-clock,

5 Fig. 3 shows the alarm-setting mechanism of the alarm-clock on a smaller scale, and

Fig. 4 is a diagrammatic illustration of the electric circuits of the alarm-clock.

The drawing does not show the timepiece completely, 10 and any usual timepiece may be used for the purpose of this invention. However, it is preferred to use an electrically driven timepiece for instance of the type disclosed in the U.S. Patent No. 2,817,207. The timepiece has a center wheel 2 mounted on a minute shaft

15 1 adapted to carry at its upper end (Fig. 1) a minute hand not illustrated. The center wheel 2 is driven for instance from the electrically sustained oscillating balance wheel as shown in the above-mentioned U.S. patent. An hour wheel 5 is mounted on a cannon 6 to

20 which the hour hand is attached in a well known manner not shown in the drawing. The hour wheel 5 is driven from the center wheel 2 in a well known manner through a minute wheel 3 and a minute-wheel pinion 4. By means of rings 7 of insulating material, for instance nylon, the hour wheel is pivoted in a cannon 8 of the unlocking wheel 9 of the alarm-clock, the unlocking wheel being electrically insulated from the dial support 10 by means of an insulating disc 11. Therefore, the unlocking wheel 9 and the cannon 8 connected

25 thereto are electrically insulated from the other parts of the timepiece and are adapted to form the one pole of the switch mechanism described below.

A contact lever 12 is pivoted on a pin 13 mounted in the unlocking wheel 9. A leaf spring 15 anchored in 30 a bore 14 of the unlocking wheel 9, engages with its free end the contact lever 12, thereby tending to displace the arm of the contact lever engaging the spring towards the center of the hour wheel 5 and of its cannon 6 respectively. A stop pin 16 is mounted in the other arm of the contact lever 12, this stop pin engaging an

35 opening 17 of the unlocking wheel 9 for limiting the angular displacements of the contact lever 12. The contact lever 12 has a curved contact surface 18 adapted for cooperation with a contact pin 19 mounted in the hour wheel 5. An actuating wedge 20 of insulating material having a control surface 21 is fixed on the contact lever 12, the said control surface 21 being slightly inclined relatively to the tangential direction or the path of the contact pin 19 near the actuating wedge. The relative position of the actuating wedge 20 and of the contact pin 19 of the hour wheel is so disposed that the contact pin 19 slowly rotating with the hour wheel 5 in the direction indicated by the arrow in Fig. 1 will engage the slightly inclined control surface 21 as shown in Fig. 1

40 and will slowly displace the contact lever 12 radially outwards towards its open position against the action of the leaf spring 15. A slide contact spring 23 having two contact lugs 24 engaging a ring slot 25 of the unlocking wheel 9 is mounted on but electrically insulated from the dial support 10.

The switch mechanism formed by the contact pin 19 and the contact lever 12 is connected into the electric circuits of the alarm-clock as diagrammatically illustrated in Fig. 4. These electric circuits comprise a radio receiver 26, preferably a transistor receiver which can be fed from one single battery 27. The one terminal of the radio receiver 26 is connected to a selector switch 28 by means of which the radio receiver may continuously be connected to its battery 27 in a lower position (Fig. 4) or may continuously be disconnected from its battery 27 in a mid position (Fig. 4) or the radio receiver may be connected

45 55 60 65 70

to its battery through the above switch mechanism controlled by the timepiece when the selector switch is in its upper position as illustrated in Fig. 4. The alarm-clock has a second battery 29 from which current pulses may be applied through a contact 31 to a driving solenoid 30 for the balance wheel of the timepiece, for instance in the manner explained in the above U.S. Patent No. 2,817,207.

The unlocking wheel 9 always remains in the position to which it has been adjusted by friction. It may be adjusted to any desired position by means of wheels 32 and 33, the so adjusted position being indicated on the dial by an alarm hand mounted on the cannon 8, but not illustrated in the drawings. The wheel 33 which is pivoted in a slot 34 and is usually maintained in engagement with the unlocking wheel 9 as shown in Fig. 3 by a leaf spring 35, only allows adjustment of the unlocking wheel 9 in anticlockwise direction in Fig. 3 because the wheel 33 is disengaged from the unlocking wheel 9 whenever adjustment of the latter in an opposite direction is attempted.

The alarm-clock operates as follows:

The hour wheel 5 and the contact pin 19 are driven by one rotation in 12 hours by the continuously running timepiece. The unlocking wheel 9 and the parts mounted thereon are adjusted to a predetermined desired position in the manner described and disclosed in detail for instance in my copending patent application Serial No. 711,623 (of the same date), this adjusted position, or more particularly the moment in which the alarm apparatus formed by the radio receiver has to be set to operation, being indicated by the said alarm hand. About one hour prior to the so adjusted moment the rounded portion of the contact pin 19 engages the upper end (Fig. 1) of the control surface 21 of the actuating wedge 20 and starts to displace the contact lever 12 radially outwards against the action of leaf spring 15. Due to its rounded portion the contact pin 19 slides along the control surface 21 without appreciable friction so that it is able to displace the actuating part 20 and the contact lever 12 connected therewith by wedge action without requiring an appreciable force. Therefore, no appreciable turning moment will be required on the hour wheel for actuating the contact lever in the manner just described. The contact lever 12 is displaced outwardly until the rear sharp edge of the control pin 19 reaches the fore sharp edge of the control surface 21 and therefore suddenly releases the actuating wedge 20. At this moment the actuating wedge 20 and the contact lever 12 are rapidly displaced radially inwards by the leaf spring 15, until the electrically conducting contact surface 18 of the contact lever 12 abuts against the contact pin 19, whereby a firm electrical connection is immediately established between parts 19 and 12. An electric circuit is thus closed from the battery 27 through the receiver 26, the selector switch 28, the contact spring 23, the unlocking wheel 9, the contact lever 12, the contact pin 19, the hour wheel 5 and through the gear train meshing with the hour wheel to the mass of the timepiece which is connected to the other terminal of the battery 27. It may be required to provide another slide contact spring similar to contact spring 23 between the mass of the timepiece and the hour wheel 5 in order to safely close the above electric circuit. Through this circuit the radio receiver is energized and a person or persons are awakened or reminded of a predetermined time by the music or speech emitted by the receiver. In accordance with the circumferential length of the curved contact surface 18 of the contact lever 12 the above circuit would remain closed for about two hours so that the receiver will in any case be operative for a period of time sufficient for awakening a person. If it is not desired to have the receiver operating for this full period of about two hours the selector switch 28 may be thrown to its mid-position in which the receiver is continuously disconnected from its power source 27. On the other hand it is possible to operate the receiver independently from the switch mechanism actuated by the timepiece by throwing the selector

switch 28 to its lower position for which the receiver is continuously connected to its power source. Of course, means may be provided in the receiver 26 for selecting different programmes.

5 When the switch mechanism has been closed in the manner described above, the contact pin 19 keeps on sliding along the contact surface 18 whereby the contact lever 12 is again slightly displaced radially outwards so that the pressure of spring 15 against the contact lever 12 slightly increases. However, since the lever arm of the contact pressure acting onto the contact lever 12 also increases due to the advance of contact pin 19, the contact pressure is maintained substantially constant throughout the contacting period between the contact lever 12 and the contact pin 19. When the contact pin 19 leaves the contact surface 18, the contact lever is again displaced radially inwards, this displacement being limited by the pin 16. As shown in the drawing the plane rear surface of the contact pin 19 is inclined relatively to a strictly radial direction so that the contact lever 12, may freely move radially inwards whenever the rear edge of the contact pin 19 leaves the control surface 21 or the contact surface 18.

What I claim is:

25 1. A time switch of the type comprising a timepiece and switch means controlled by the said timepiece, and adjusting means in the said switch means for selecting a predetermined moment in which the said switch means are closed by the said timepiece, a contact lever in the said switch means, having an open and a closed position, a directive force continuously acting onto the said contact lever and tending to shift it into its said closed position, an actuating pin operatively associated with the said contact lever and driven by the said timepiece, insulating actuating means being interposed between the said actuating pin and the said contact lever for displacing the said contact lever from its said closed position towards its said open position, and the said actuating pin and contact lever forming cooperating contact members of the said switch means.

2. A time switch according to claim 1, comprising an adjustable unlocking wheel and an hour wheel in the said timepiece, the said contact lever being mounted on the said unlocking wheel and the said actuating pin being mounted on the said hour wheel.

3. A time switch according to claim 1, comprising an actuating part of insulating material on the said contact lever, a control surface on the said actuating part, a path along which the said pin is displaced near the said actuating part, the said control surface being slightly inclined relatively to the path of the said pin and the said pin engaging the said control surface during its movement near the actuating part, an end on the said actuating part where the said pin leaves it and a sharp edge on the said actuating part limiting the said control surface at its said end.

4. A time switch according to claim 3, comprising a direction in which the said pin is displaced, the said pin having a rounded portion at its front side as seen in the said displacing direction of the pin and having a sharp edge limiting the said rounded portion, the said pin engaging and supporting the control surface of the said actuating part with its said rounded portion but allowing sudden engagement of metallic portions of the said contact lever and the said pin when the rounded portion of the pin leaves the said control surface of the actuating part of the contact lever.

5. A time switch according to claim 2, the said unlocking wheel being electrically insulated from all other portions of the time switch and adapted for being connected to the live terminal of an electric power source.

6. A time switch of the type comprising a timepiece, an hour wheel in the said timepiece, switch means operable by the said timepiece, an adjustable unlocking wheel

mounted coaxially with the said hour wheel, the said switch means being mounted on the said unlocking wheel, a contact member in the said switch means having a closed position and an open position, means continuously tending to bring the said contact member into its said closed position, actuating means operatively connected to the said hour wheel and operatively associated with the said contact member, adapted to bring the said contact member into its said open position under control of the said hour wheel, a releasing relative position between the said hour wheel and the said unlocking wheel and releasing means operatively associated with the said contact member and operatively connected to the said hour wheel, adapted to release the said contact member from its said open position into its said closed position when the hour wheel and the said unlocking wheel are in their said releasing position.

7. A time switch of the type comprising a time piece, an hour wheel in the said timepiece, switch means, unlocking means operatively associated with the said switch means and adapted for adjusting the position of the switch means relatively to the said hour wheel, a contact member in the said switch means having a closed position and an open position, means continuously tending to bring the said contact member into its said closed position, actuating means operable by the said hour wheel and operatively associated with the said contact member, adapted to bring the said contact member into its said open position under control of the said hour wheel, releasing means operable by the said hour wheel and a releasing posi-

tion between the said releasing means and the said contact member, the said contact member being released from its said open position into its said closed position when in its said releasing position.

8. A time switch of the type comprising a timepiece and switch means controllable by the said timepiece, an hour wheel in the said timepiece and unlocking means adjustable for preselecting the instant at which the switch means is to be closed, an open position and a closed position for the said switch means, a directive force continuously acting onto the said switch means and tending to shift it into its said closed position, a charging period for the said switch means, means operable by relative displacement between the said hour wheel and the said unlocking means respectively for slowly displacing the switch means from its closed position towards its open position during the said charging period, and releasing means operable at a predetermined relative position of the said hour wheel and unlocking means respectively for suddenly releasing the said switch means to its closed position at the end of the said charging period.
